(57) **CLAIM**

The ornamental design for a “torso/waist sling,” as shown and described.

DESCRIPTION

FIG. 1 is a front elevation of a torso/waist sling showing a first embodiment of our new design;

FIG. 2 is a rear elevation thereof;

FIG. 3 is a top plan view thereof;

FIG. 4 is a bottom plan view thereof;

FIG. 5 is a side elevation thereof, the opposite side elevation is a mirror image of FIG. 5;

FIG. 6 is a perspective view thereof;

FIG. 7 is a front elevation of a second embodiment of the torso/waist sling;

FIG. 8 is a rear elevation of the second embodiment;

FIG. 9 is a top plan view of the second embodiment;

FIG. 10 is a bottom plan view of the second embodiment;

FIG. 11 is a side elevation of the second embodiment, the opposite side is a mirror image of FIG. 11; and,

FIG. 12 is a front elevation of a third embodiment of the torso/waist sling, the appearance of the rear, top, bottom and sides of the third embodiment are the same as the first embodiment.

The broken lines in the drawings are for illustrative purposes only and form no part of the claimed design. Some of the views are shown drawn on different scales.
